UNITED STATES PATENT OFFICE.

JOHN NEEDRE, OF NEWPORT NEWS, VIRGINIA.

DRY CLEANER.

Application filed July 2, 1925. Serial No. 41,206.

To all whom it may concern:

Be it known that I, JOHN NEEDRE, a citizen of the United States, residing at Newport News, in the county of Warwick and 5 State of Virginia, have invented certain new and useful Improvements in Dry Cleaners, of which the following is a specification.

This invention appertains to a novel machine utilized in the process of cleaning 10 clothes and the primary object of the invention is to provide a single machine for dry cleaning clothes, in which the clothes can be first thoroughly cleansed by the gasoline, second the gasoline extracted therefrom and 15 third the clothes deodorized so that all odor of the gasoline will be effectively removed therefrom.

A further object of the invention is to provide a single machine for cleaning clothes, 20 extracting the cleaning fluid from the clothes and deodorizing the same, which will be of a compact nature and eliminate the necessity of providing three different machines for cleaning, extracting and deodorizing.

25 A further object of the invention is the provision of a novel cleaning, extracting and deodorizing machine for clothes, embodying a novel vat for receiving the cleaning fluid arranged in a novel manner within a supporting frame, and novel means for mounting the clothes receiving cylinders within the vat.

30 A further object of the invention is the provision of novel means for introducing the cleaning fluid within the vat and novel means for rotating the cylinders within the vat.

35 A further object of the invention is the provision of novel means for rotating the cylinders after the draining of the gasoline from the vat for removing or extracting the gasoline or cleaning fluid from the clothes themselves by centrifugal action.

40 A further object of the invention is the provision of novel means mounted directly within the vat for deodorizing the clothes after the gasoline has been drained therefrom, said means including the novel arrangement of steam pipes for forming a radiator to vaporize the remaining gasoline, the gasoline vapors being fanned out of the clothes by the rapid rotation of the clothes cylinder.

45 A still further object of the invention is to provide an improved machine of the above character, which will be durable and efficient

in use, one that will be simple and easy to manufacture and one which can be placed upon the market at a reasonable cost.

With these and other objects in view, the 60 invention consists in the novel construction, arrangement and formation of parts, as will be hereinafter more specifically described, claimed, and illustrated in the accompanying drawings, in which drawings:

65 Figure 1 is a top plan view of the improved machine,

Figure 2 is a side elevation of the same,

Figure 3 is a transverse section through the improved machine illustrating the construction and arrangement of the vat within the supporting frame, and the clothes receiving cylinders within the vat,

Figure 4 is a central longitudinal section through the vat showing the clothes receiving cylinders in side elevation,

Figure 5 is an end elevation of the improved device, parts thereof being shown in section,

Figure 6 is a detail fragmentary elevation 80 illustrating the means for operating the clutch for throwing the clothes receiving cylinders in high speed,

Figure 7 is a section through the same taken on the line 7—7 of Figure 6,

Figure 8 is a detail sectional view illustrating the stub shaft carried by the vat frame for receiving the drive gear, when the same is moved in engagement with the driven gear for the clothes receiving cylinders,

90 Figure 9 is a transverse section through a modified form of clothes receiving cylinder.

Referring to the drawings in detail, where-in similar reference characters designate corresponding parts throughout the several 95 views, the letter A generally indicates the improved machine for cleaning the clothes, extracting the cleaning fluid from the clothes and for deodorizing the clothes after the extracting of the cleaning fluid therefrom.

The improved machine A comprises a supporting frame 5, which can be constructed from any material, such as wood or the like and the same embodies a front and rear pair of corner standards 6 and 7. The front pair

100 of standards 6 are connected together by upper and lower longitudinally extending brace bars 8 and 9, and by diagonally extending brace bars 10. The rear pair of corner standards 7 are connected substantially in

105 the same manner, and the said front and rear pairs of the standards can be connected

65

110

together by transverse brace bars 11. This frame 5 can be supported in any preferred manner, such as by feet 12 and these feet can be connected by arcuate transversely extending beams 13.

Arranged within the frame 5 is the vat 15, which is preferably formed of metal, of a non-corrodible character. This vat 15 embodies side walls 16 and 17, end walls 18 and arcuate bottom walls 19 and an arcuate top wall 20. It is to be noted that the bottom wall 19 is of an arcuate shape, in order to permit the cleaning fluid to naturally drain toward the longitudinal center thereof. The sides and bottom of the vat are spaced from the frame and suitable compression springs 21 are arranged between the vat and the frame for absorbing shock and to reduce the transmission of vibration from the vat to the frame incident to the rotation of the clothes receiving members within the vat, as will be now described.

The novel clothes receiving device is generally indicated by the reference character 25 and the same includes the clothes receiving cylinders 26, which are formed of metal of a non-corrodible character and these cylinders are corrugated for acting on the clothes. Each of the cylinders 26 is perforated throughout as at 27 so as to permit the free flow of cleaning fluid therethrough. These cylinders are fitted against hub plates 28 and are confined against said hub plates by the means of annular bands 29 which extend entirely about the cylinders adjacent to the terminals thereof and at a point intermediate the ends thereof. These bands 29 are brought into intimate contact with the said cylinders by means of spokes 30 which extend radially from the hub plates and through the bands, the outer terminals of the spokes having threaded thereon nuts 31 for engaging the said bands.

In order to permit the introduction of the clothes within the cylinders, each cylinder is provided with sliding doors 32 on each side of the intermediate band 29. The doors 32 are mounted in guide ways 33 formed in the said cylinder and can be maintained in a closed position in any desired way, such as by the means of a suitable fastener.

The top wall 20 of the vat or tank 15 is also provided with a pivoted closure or door 34, which can also be maintained in a closed position by the use of a suitable fastener or catch 35. I prefer to mount the door in such a way, as to prevent the escape of fluid around the same during the operation of the device. By rotating the bands 29, the cylinders 26 can be brought into close proximity to the door 34 one at a time, whereby the clothes can be readily placed in or removed from the said cylinders.

In order to permit the rotation of the clothes receiving device, a drive shaft 36

is extended axially through the hub plates 28 and these plates are secured thereto in any desired way for rotation therewith. Bearings 37 are carried by the end walls 18 of the vat and the bearings can be provided with any preferred type of stuffing boxes 38 so as to prevent the leakage of the cleaning material around the shaft, from the vat. The drive shaft extends through the end walls 18 and beyond the vat. The means for rotating the entire clothes receiving device 25 forms an important part of the invention and this means, is so arranged, as to permit the easy rotation of the said clothes receiving device at various speeds, for a purpose, which will be hereinafter more fully described. It is to be noted that one end of the shaft 36 is provided with a relatively large spur gear wheel 39, with which is adapted to mesh a relatively small drive spur gear wheel 40 feathered on a drive shaft 41. This drive shaft 41 is supported by suitable bearings 42 carried by a supporting bracket 43. This bracket can be connected in any desired way, such as by laterally extending arms 44 with the main frame 5. The drive shaft 41 has mounted thereon drive pulleys 45 and 46 and an idle pulley 47. Around the drive pulley 45 is trained a straight belt 48, while a cross belt 49 is trained about the pulley 46. These belts 48 and 49 are adapted to be driven from a suitable line shaft and it is obvious that by shifting one belt or the other to the idle pulley, that the drive shaft 41 can be driven in either direction.

In order to bring the drive spur gear 40 into and out of meshing engagement with the spur gear 39, so as to rotate the clothes receiving cylinders I provide a shift lever 50 which is rockably mounted as at 51, at its lower end to a suitable supporting bracket 52 carried by the arms 44. This lever 50 is operatively connected to the gear for sliding the same along the shaft 41. In order to form an effective support for the drive gear 40 when the same is shifted into meshing engagement with the gear 39 I provide a stub shaft 53, which is rotatably mounted in a suitable bearing 54 carried by the frame 5. This stub shaft extends over the spur gear 39 in direct alignment with the drive shaft 41 and the axial center of the gear 40 is provided with an opening to receive the same, when the gear 40 is moved over the spur gear 39.

In order to bring about the stopping of the shaft 36 and the clothes receiving device 25 the inner face of the gear 39 can be provided with a brake band 55, which is adapted to be engaged by a brake shoe 56. This brake shoe 56 is carried by a lever 57 pivotally secured as at 58 to the frame 5. It is obvious that by operating the lever the

shoe 56 can be brought into and out of contact with the brake band 55. When the shaft 36 is driven from the spur gear 40, the clothes receiving device will be driven at 5 a relatively slow rate of speed. In order to drive the shaft 36 at a relatively high rate of speed, a pulley wheel 60 is arranged on the opposite side of the vat and frame and this pulley wheel is rotatably mounted upon 10 a shaft 61 which is rotatably carried by a swinging arm 63. The lower end of the arm extends downwardly and inwardly at an angle and is connected by means of a pin and slot connection as at 64, with a supporting bracket 65 carried by the frame 5 of the cleaning device.

A suitable supporting bracket 66 is connected with the main frame 5 of the device and this frame carries a bearing 67 in which 20 is rotatably mounted a stub shaft 68. A universal joint 69 is utilized for connecting the stub shaft 68 with the drive shaft 36. The pulley 60 is adapted to be connected with the stub shaft 68 by the use of a suitable clutch 70 of the friction type and it is 25 obvious that by shifting the pulley the same can be operatively connected to said stub shaft. The pulley 60 is adapted to be operated from the line shaft (not shown) for 30 operating the drive shaft 41 heretobefore described.

The provision of the universal joint 69 prevents the transmission of the vibrations from the clothes receiving device 25 to the 35 flush.

The means for operating the clutch 70 includes a short transverse shaft 71 provided with a bearing 72 carried by a laterally extending arm 73 bolted or otherwise 40 secured to the supporting bracket 66. This arm 73 slidably extends through a guide 74 on the lever 63 and this guide 74 is provided with openings 75 in which are fitted cams 76 eccentrically mounted on the shaft 45 71. One end of the shaft 71 is provided with a manipulating crank 77. It is obvious that by turning the crank 77 that the cams 76 will be operated by acting on the guide 74 and thus sliding the lever 63 toward or away 50 from the vat, as the case may be. I prefer to use a contractile coil spring 78 connected with the lever and the bracket 66 for normally urging the lever toward the vat to facilitate the throwing in of the clutch 70. Any 55 other preferred means may be utilized for operating the clutch 70. The extreme lower end of the vat 15 at the longitudinal center thereof has communicating therewith a drain pipe 79. The drain pipe 79 has 60 connected thereto a coupling 80 to either end of which can be connected the leader pipe 81 which can lead to a storage tank for the cleaning fluid. This pipe 81 is provided with a coil 82 which is 65 provided for the purpose of taking up shock,

The upper end of the vat has communicating therewith a feed pipe 83 for permitting the filling of the vat with the gasoline or other cleaning fluid. The extreme upper end of the vat is provided with a vapor outlet pipe 70 84, as clearly shown in the drawings.

Leading laterally from one end of the tank is the steam pipe 85 for communicating with the steam coil and this pipe can also have a single coil incorporated therewith to absorb 75 vibrations. The purpose of the steam coil will now be described.

In order to permit the ready deodorizing of the garments after the same have been cleaned and the cleaning fluid extracted 80 therefrom, a steam coil 86 is arranged directly within the vat adjacent to the lower end thereof. This coil, which is in the nature of a radiator entirely surrounds the garment receiving device 25. The pipe 85 can lead 85 to any suitable source of steam supply, and an outlet pipe is also provided for said steam coil.

As has heretobefore been intimated, the clothes receiving device 25 is rotated within 90 the vat and the cleaning fluid placed in the vat, and in order to reduce the splashing of the cleaning fluid incident to the rotation of the clothes receiving device, suitable outwardly extending flanges 88 are arranged 95 within the vat at spaced points. These flanges 88 project outwardly so as to catch the said cleaning fluid.

In operation of the improved device, the vat 15 is filled with cleaning fluid, such as 100 gasoline, to a point slightly above the center thereof and the clothes are introduced into the cylinders 26 in the manner heretofore described. An equal amount of clothes is preferably placed in each cylinder, so that 105 the clothes receiving device 25 will be balanced. After the clothes are placed in the cylinders the clothes receiving device is rotated through the medium of the shaft 41, 110 the desired length of time. The rotation of the cylinders through the cleaning fluid will effectively remove all dirt from the clothes and after the clothes receiving device has been rotated the desired length of time, the 115 rotation of the device is stopped and the gasoline is drained from the vat through the pipe 79. The cleaning operation of the clothes is now completed and the machine is ready for its second operation, namely 120 the extracting of the cleaning fluid from 125 said clothes.

The pulley 60 is connected with the shaft 36 through the medium of the clutch 70 and the clothes receiving device 25 is rotated at a relatively high rate of speed, preferably, at eight hundred revolutions per minute. This rapid rotation of the clothes receiving device will permit the throwing off of the remaining gasoline from the clothes by centrifugal action and after the clothes

receiving device has been rotated a desired length of time it will be found the clothes will be in a substantially dry condition after which the power is closed off. The gaso-

5 line thrown off of the clothes is permitted to drain from the pipe 79. By this manner the gasoline is readily extracted from the clothes.

In order to remove all odor of the gasoline from the clothes, steam is permitted to flow into the steam coil 86 which will heat the clothes and the vat and vaporize any remaining gasoline therein. The clothes receiving device is now rotated at a high rate 10 of speed for fanning the vapors out of the clothes and after the clothes receiving device has been rotated the desired length of time, the power is turned off and the cylinders are permitted to remain stationary a few minutes after which the cylinders are again turned slow for about ten or fifteen minutes. The steam is now shut off and the cylinders are allowed to revolve at a high rate of speed through the medium of the shaft 68 and pulley 60 until all of the gasoline vapors have been entirely fanned out. At the end of this operation, it will be found that the clothes will be completely deodorized.

15 20 25 30 35

When the vat is filled with gasoline, it is preferred to support the same through the medium of suitable blocks 90 which are placed between the bottom wall 19 of the vat and the brace bars of the main supporting frame. These blocks can be removed during the cleaning fluid extracting and deodorizing process.

In certain instances I prefer to use a type of clothes receiving device generally indicated by the reference character 100 as shown in Figure 9 of the drawings. This clothes receiving device 100 embodies a large cylinder 101 which can be secured to the shaft 36. The cylinder 101 is divided 40 45 50 into four compartments 102 by suitable spaced tubes 103 arranged at quarters within the cylinders. The outer wall of the cylinder at each of the compartments 102 is provided with suitable doors 104, by 55 means of which the clothes can be introduced within the said chambers.

From the foregoing description, it can be seen that I have provided a cleaning

machine for cleaning clothes, extracting the cleaning fluid from the clothes and removing all odor of the cleaning fluid from the clothes.

Changes in details may be made without departing from the spirit or the scope of this invention, but—

60 65 70 75 80 85 90 95 100

What I claim as new is:

1. In a clothes cleaning apparatus, a support, a vat arranged in the support, means for resiliently supporting the vat within the support, a rotatable clothes receiving device arranged in the vat, means for rotating the clothes receiving device at a relatively low rate of speed from one end of the vat, means including a guide shaft arranged at the opposite end of the vat for 70 rotating the garment receiving device at a relatively high rate of speed, and a universal joint connection between the said drive shaft and the garment receiving device.

2. In a garment cleaning device, a vat, a clothes receiving device rotatably mounted within the vat including spaced hub plates having peripheral notches, a plurality of spaced perforated corrugated cylinders fitted within the notches of the hub plates, means connecting the cylinders together and to the hub plates, and means for operating the clothes receiving device in said vat.

3. In a garment cleaning device, a vat, a drive shaft extending through the vat, means for preventing the leakage of fluid from the vat around the drive shaft, a clothes cleaning device mounted within said vat on said drive shaft including a plurality of cylindrical garment receiving cylinders 90 disposed at spaced points around the shaft, spaced bands extending around the cylinders and clamping the same to the shaft, the said clothes receiving cylinders being perforated throughout, means for rotating the shaft, 95 means for introducing and draining the cleaning fluid in the vat, a solid steam coil arranged in the vat surrounding the lower end of the clothes receiving device for vaporizing any remaining gasoline from the clothes after the gasoline has been drained from the vat.

In testimony whereof I affix my signature.

JOHN NEEDRE.
